UNITED STATES PATENT OFFICE.

WILLIAM CHARLES SMITH, OF MINNEAPOLIS, MINNESOTA.

VESSEL-PROPELLION DEVICE.

Application filed October 13, 1927. Serial No. 225,926.

My invention relates to vessel propulsion devices and has for its object to provide a pair of revoluble members supporting an endless carrier, said carrier being provided 5 with paddles pivoted thereto and adapted to project outwardly therefrom or to lie substantially in the plane of said carrier.

Another object of the invention resides in providing pairs of facing stops adapted to be 10 alternately engaged by said paddles for holding the same from movement in either direction from projected position so as to cause the same to transmit tractive effort in propelling the vessel in either direction.

15 Another object of the invention resides in constructing said revoluble member so as to cause the paddles thereof to move into the plane of said carrier upon the engagement thereof with said revoluble members.

20 Another object of the invention resides in reversing the position of said paddles when lying substantially in the plane of said carrier so as to permit of said carrier traveling in a reverse direction for causing the vessel to move backwards.

30 A feature of the invention resides in arranging said paddles for transverse movement so as to cause the same to engage either of said sets of stops and to further arrange said paddles with the pintles thereof projecting outwardly beyond the carrier and to provide cam members for shifting all of said pintles during the operation of said carrier.

35 Another object of the invention resides in providing an arcuate guideway adapted to engage lugs formed upon the ends of said paddles and to reverse the position of said paddles relative to said carrier upon movement thereof.

40 A still further object of the invention resides in providing directing members for directing the said lugs into said guideways.

45 Another object of the invention resides in forming the paddles with air chambers for causing the same to float into horizontal position so as to allow the paddles to pass around said revoluble members during the reversal of the paddles.

50 A feature of the invention resides in mounting the cams for shifting said paddles upon a shiftable structure adapted to be simultaneously operated with the operation of said directing members so as to cause each of the paddles to be shifted during the reversal of the position of the same relative to said carrier.

With the foregoing and other objects in view, which will appear in the following description, the invention resides in the novel combination and arrangement of parts and in the details of construction hereinafter described and claimed.

In the drawings:

Fig. 1 is a side elevational view of a small vessel illustrating the application of my invention thereto.

Fig. 2 is a side elevational view of a portion of the propulsion device removed from the vessel.

Fig. 3 is a plan view of the structure shown 70 in Fig. 2 and drawn to a somewhat larger scale.

Fig. 4 is a sectional view taken substantially on line 4—4 of Fig. 3.

Fig. 5 is a fragmentary side elevational 75 view of a portion of one of the chains with parts thereof removed to illustrate the method of mounting the paddles thereon.

For the purpose of illustrating my invention, I have shown in Fig. 1 a vessel A which may be a boat of any desired type adapted to be propelled by motive power. At the stern of this boat I have illustrated my invention in its entirety at B, which is installed within a housing 10 formed in the bottom of the boat and adapted to enclose the propulsion device along the upper portion and sides thereof. Within the boat is positioned an engine 11 of any desired type which is provided with a shaft 12 extending through the 85 housing 10 and arranged to propel the device, as will presently become apparent.

The invention proper as best shown in Figs. 2 and 3, comprises two longitudinal beams 13 and 14 which are connected together at suitable intervals with cross members 15 riveted thereto. Near the ends of the beams 13 are arranged bearings 16 in which are journaled two shafts 17 and 18 carrying drums 19 and 20. The shaft 18 is 90 driven from the shaft 12 through engine 11. The drums 19 and 20 may be constructed in any suitable manner and are preferably formed seven sided, as illustrated, to accommodate the particular type of carrier chains 105 shown in the drawings. The propulsion device which is supported on the beams 13 and 14 is mounted in the boat by suitable structures secured to the framework of the boat proper and carrying the said beams 13 110 and 14.

Over the two drums 19 and 20 pass two

chains 21 and 22, each arranged with an upper and lower run 23 and 24. These chains consist of spaced link bars 25 and 26 which are pivotally connected to blocks 27 which 5 serve as suitable spacers and also connect the said link bars together. These chains ride freely upon the drums 19 and 20 and it will be noted that the corners of said drums indicated at 28 are cut away to accommodate the 10 blocks 27 of the said chains. The lower runs 24 of the chains 21 and 22 run free and are arranged to project below the keel of the boat, as shown in Fig. 1, while the upper runs 21 are supported on tracks 29 secured 15 to the cross members 15 of the supporting structure of the device.

In the centers of each of the link bars 25 and 26 are pivotally mounted pintles 30 which extend completely across both chains and may 20 be slid transversely relative to the same. These pintles have secured to them paddles 31 which are adapted to normally extend outwardly therefrom as illustrated on the lower run 24 of the chains 21 and 22, in Fig. 2, 25 or which may be swung upon said pintles to occupy positions as illustrated in conjunction with the upper runs 23 of said chains in the same figure, said movement being permitted through the swinging of said paddles 30 upon the pintles 30. In between the respective link bars 25 and 26 are arranged levers 32 and 33 which are mounted upon said pintles and are connected at their outer portions 35 to the paddles 31. These levers are 35 best shown in Fig. 5 and terminate at their lower ends in cams 35 which normally project outwardly beyond the contacting surface of the chains 21 and 22, when said paddles are in projected position. When the chains 21 and 22 engage the drums 19 and 20, the cams 35 of levers 32 and 33 engage the surface of 40 said drums and cause the said levers together with the paddles 31 connected therewith, to be moved into positions substantially coinciding with the plane of said chains. In this manner, as the two chains travel around the drums 19 and 20, the paddles are permitted to extend into projected position along the lower runs 24 and are caused to lie substantially 45 in the plane of the chains when moving along the upper runs of the same.

For holding the paddles 31 in projected position, the following construction is employed which is best shown in Figs. 5 and 3. 55 Along the facing surfaces of each of the link bars 25 and 26 of the chains 21 and 22 are arranged oppositely disposed stops 36 and 37. These stops are arranged with inclined surfaces 38 and vertical surfaces 39 60 adapted to cooperate with the extended portions 40 of levers 32 or with portions of said levers indicated at 41 adjacent the cams 35. It will be noted that the width of the levers 32 and cams 35 is less than the distance between 65 one of the link bars 25 or 26 and the

opposite stops 36 or 37 so that said levers 32 may be shifted into engagement with either of the stops. By means of this construction the said levers may be held from movement from their projected positions in either direction so that the device will operate to propel the vessel in either a forward or reverse direction, or when moved in the plane of the chains, rest upon the inclined surfaces of said stops. 75

As before stated, the pintles 30 which carry the levers 32 and 33 and the paddles 31 are slidably arranged in the link bars 25 and 26 of the respective chains 21 and 22 so that said levers may be shifted to position the same for 80 operation of the carrier in either forward or reverse direction. For this purpose the said pintles are of such a length that the extreme ends 42 and 43 thereof extend outwardly beyond the outer faces of the link bars 26. 85 The ends of these pintles are adapted to be engaged by two cams 44 and 45 which are moved in unison and which serve to shift the same, as will presently be described. The cams 44 and 45 are operated as follows: Beneath the two tracks 29 are arranged three shafts 46, 47 and 48 which are journaled in bearings 49 formed on the underside of said track and rigidly secured thereto. The shaft 47 is arranged for rotation within its bearings 90 and is held from axial movement by means of two collars 50 and 51. The two shafts 46 and 48 are connected together at their two ends by means of cross heads 52 and 53 which are rigidly secured thereto and are arranged for sliding motion in their bearings 49 and upon the shaft 47. These two cross heads have rigidly attached to them the cams 44 and 45 so that when the said cross heads are reciprocated, said cams are drawn in the paths of 95 the ends 42 and 43 of pintles 30 so as to shift the same into engagement with either of the sets of stops 36 or 37. 100

For shifting the cams 44 and 45 I construct the cross heads 52 and 53 with bosses 54 and 55 slidable along the shaft 47. These bosses are constructed with spiral cam surfaces 56 and 57 which are adapted to coact with complementary spiral cam surfaces 58 and 59 formed on the hubs 60 and 61 of the two 115 levers 62 and 63 rigidly secured to the ends of the shaft 47. With this construction, the cams 44 and 45 may be simultaneously shifted in either direction depending upon the movement of said levers 62 and 63. The lever 62 extends upwardly beyond the device proper 120 and may have attached to it a rod 64 by means of which the device may be manually operated. It will be noted that such play exists between the bosses 54 and 55 and the hubs 60 and 61 so that the lever 62 may be moved from one extreme position back into its intermediate position without affecting the shifting of the respective paddles. This 125 allows the machine to be brought back to 130

neutral without requiring the same to remain in either of its extreme positions during the operation of the device.

For the purpose of reversing the position 5 of the paddles 31 in traveling over the drums 19 and 20 I attach to the center portions of each of the tracks 29 a casting 65 best illustrated in detail in Fig. 4, which is formed with an arcuate guideway or groove 66 open at 10 its two lower ends which face the chains 21 and 22 as the same pass through said tracks. At the lowermost portions of this guideway are pivotally mounted fingers 67 and 68 which are attached to shafts 69 and 70 journaled in 15 said casting 65 and extending completely through the same where said shafts have attached to them arms 71 and 72. These fingers are adapted to swing from their two extreme positions shown in full and dotted lines in 20 Fig. 4 in conjunction with arms 71 and 72 and are arranged to catch lugs 75 formed on the extreme ends of the levers 32 and to direct the same into the groove or guideway 66. This has the effect of elevating the paddles 31 and 25 causing the same to reverse in direction as the same pass along the groove so that when said lugs leave the groove 66 the paddles 31 extend in the opposite direction from which they extend on the other side of said casting 30 65.

The fingers 67 and 68 are manipulated by means of the levers 62 and 63 which are adapted to engage the extreme ends of the arms 71 and 72 and cause the same to swing 35 to throw the fingers 67 and 68 into either of their extreme positions. Arms 71 and 72 have attached to them tension coil springs 76 and 77 which are so arranged as to hold said fingers 66 and 67 in either of their extreme 40 positions. As soon as the arms 71 and 72 are brought over dead center with respect to these springs, said springs throw said levers to their extreme positions.

For resetting the fingers 67 and 68 in normal position, the following construction is used: On the end of each of said fingers is provided an inwardly extending beam 78 which is adapted to engage a shoulder 79 formed on each of the levers 32 and 33. 45 When the lugs 75 are entering the groove 66, the said shoulder 79 follows along upon the beam 78 and into the groove 66 until the levers 32 and 33 are sufficiently elevated to cause the lowermost end of said shoulder to clear said beam. The said lugs 75 then continue their travel through the groove 66 reversing the direction of the paddles, as before stated, until the said lugs leave the said groove. After the same leave the groove the 50 shoulders 79 depress the fingers 68 slightly by engagement with the beam 78, but only in amount sufficient to permit the said lugs to be withdrawn from groove 66. Upon leaving the same the said fingers through the action 55 of the springs 76 and 77 immediately throw

the said fingers back into normal position. When all of the paddles 31 have been reversed the shoulders 79 act as cam surfaces and engage the beams 78 and cause the fingers 67 to be again elevated. As soon as the fingers pass 60 dead center the same snap back into normal position leaving the levers 32 and 33 free from the same and adapted to pass along the tracks 29 without obstruction. It will be noted that the said tracks 29 are depressed as 65 indicated at 80 to permit the cams 35 on said levers 32 and 33 to swing during the reversal of the paddles 31. It will readily be comprehended that by simply throwing the lever 62 into either direction so as to engage either 70 of the arms 71 and 72 that the fingers 67 or 68, as the case may be, are brought into operative relation to cause the reversal of the paddles. To cause the paddles to lie horizontally 75 along the lower run so as to enable the same to travel over the drums in reversed position, each paddle is formed at its outer end with an air space 81 which tends to float the said paddles and hold them in substantially horizontal 80 position. Such buoyancy is further aided 85 through the resistance offered by the water to the passage of the paddles therethrough which causes the paddles to swing into the plane of the carrier. As soon as all of the paddles have been reversed, the power transmitted to the drum 18 from engine 11 can also be reversed and the device will propel the 90 vessel in a reverse direction.

My invention is highly advantageous in that a great amount of power may be transmitted so as to give a large amount of tractive effort together with high velocity. The device will function so as to propel the vessel in either direction by simply operating one lever to reverse the paddles and another lever 100 to reverse the power after the reversal of the paddles.

Changes in the specific form of my invention, as herein disclosed, may be made within the scope of what is claimed without departing from the spirit of my invention.

Having described my invention, what I claim as new and desire to protect by Letters Patent is:

1. A vessel propulsion device comprising 115 spaced revoluble members, an endless carrier passing around said members, a plurality of paddles pivoted to said carrier and adapted to extend outwardly therefrom or to swing substantially into the plane of said carriers, 120 said paddles being movable transversely relative to said carrier, and pairs of stops for holding said paddles from movement in either direction while in extended position, and means for shifting said paddles laterally to 125 bring the same in engagement with either set of stops.

2. A vessel propulsion device comprising 130 spaced revoluble members, an endless carrier passing around said members, a plurality of

5 paddles pivoted to said carrier and adapted to extend outwardly therefrom or to swing substantially into the plane of said carriers, said paddles being movable transversely relative to said carrier, and pairs of stops for holding said paddles from movement in either direction while in extended position, and means for shifting said paddles laterally to bring the same in engagement with either 10 set of stops, and means operated by said shifting means for reversing the position of said paddles relative to said carrier when substantially positioned in the plane thereof.

15 3. A vessel propulsion device comprising spaced revoluble members, an endless carrier passing around said members, a plurality of paddles pivoted to said carrier and adapted to extend outwardly therefrom or to swing substantially into the plane of said carriers, said 20 paddles being movable transversely relative to said carrier, and pairs of stops for holding said paddles from movement in either direction while in extended position, means for shifting said paddles laterally to bring the 25 same in engagement with either set of stops, an arcuate guideway positioned in proximity to said carrier, lugs on the end of said paddles adapted to pass through said guideway, said paddles being adapted to reverse in direction upon passage therethrough, and means for directing said lugs into said guideway.

25 4. A vessel propulsion device comprising spaced revoluble members, an endless carrier passing around said members, a plurality of paddles pivoted to said carrier and adapted to extend outwardly therefrom or to swing substantially into the plane of said carriers, said paddles being movable transversely relative to said carrier, and pairs of stops for holding said paddles from movement in either direction while in extended position, means for shifting said paddles laterally to bring the same in engagement with either set of 45 stops; an arcuate guideway positioned in proximity to said carrier, lugs on the end of said paddles adapted to pass through said guideway, said paddles being adapted to reverse in direction upon passage therethrough, and means for directing said lugs into said guideway, and means for rendering said directing means inoperative upon the reversal of all of said paddles.

55 5. A vessel propulsion device comprising spaced revoluble members, an endless carrier passing around said members, a plurality of paddles pivoted to said carrier and adapted to extend outwardly therefrom or to swing substantially into the plane of said carriers, said paddles being movable transversely relative to said carrier, and pairs of stops for holding said paddles from movement in either direction while in extended position, means for shifting said paddles laterally to

65 bring the same in engagement with either set of stops, an arcuate guideway positioned in proximity to said carrier, lugs on the end of said paddles adapted to pass through said guideway, said paddles being adapted to reverse in direction upon passage therethrough, and means for directing said lugs into said guideway, said directing means being simultaneously operable with said shifting means.

70 6. A vessel propulsion device comprising a pair of revoluble drums, a pair of chains passing over each end of said drums, said chains comprising spaced link bars pivoted together, levers pivoted to said link bars at the centers thereof, paddles attached to said levers, oppositely facing stops formed on the inner 75 surfaces of said link bars for alternate engagement with said levers for holding said paddles from movement from extended position in either direction, said levers being transversely movable, and means for shifting 80 said levers to bring the same in engagement with either set of stops.

85 7. A vessel propulsion device comprising a pair of revoluble drums, a pair of chains passing over each end of said drums, said 90 chains comprising spaced link bars pivoted together, levers pivoted to said link bars at the centers thereof, paddles attached to said levers, oppositely facing stops formed on the inner surfaces of said link bars for alternate 95 engagement with said levers for holding said paddles from movement from extended position in either direction, said levers being transversely movable, said levers having the pintles thereof extending outwardly beyond the surface of said chains, a member shiftable transversely relative to said chains, spaced cam members formed on said shiftable member adapted to straddle said chains and to alternately engage the pintles on opposite 100 sides of said paddles for shifting said levers into engagement with either of said set of stops.

105 8. A vessel propulsion device comprising a pair of revoluble drums, a pair of chains 110 passing over each end of said drums, said chains comprising spaced link bars pivoted together, levers pivoted to said link bars at the centers thereof, paddles attached to said levers, oppositely facing stops formed on the inner surfaces of said link bars for alternate 115 engagement with said levers for holding said paddles from movement from extended position in either direction, said levers being transversely movable, said levers having the pintles thereof extending outwardly beyond the surface of said chains, a member shiftable transversely relative to said chains, spaced cam members formed on said shiftable member adapted to straddle said chains and to alternately engage the pintles on opposite sides 120 of said paddles for shifting said levers into engagement with either of said set of stops,

75

and means simultaneously operable with said shiftable device for reversing the direction of said paddles relative to said chains.

9. A vessel propulsion device comprising spaced revoluble members, an endless carrier passing around said members, a plurality of paddles pivoted to said carrier and adapted to extend outwardly therefrom, stops on said carrier, two for each paddle, one of said stops being adapted to engage the corresponding paddle on one side thereof for holding said

paddle from swinging in one direction, and the other of said stops being adapted to engage the paddle on the opposite side thereof for holding said paddle from swinging in the opposite direction, and means for alternately bringing each successive paddle into engagement with either of the stops corresponding therewith.

In testimony whereof I have affixed my signature to this specification.

WILLIAM CHARLES SMITH.
